United States Patent Office

Des. 185,116
Patented May 12, 1959

185,116

SOLE

George H. Bingham, Jr., and Clarence E. Phillips, Taneytown, Md., assignors to Cambridge Rubber Company, Cambridge, Mass., a corporation of Maryland

Application October 8, 1957, Serial No. 48,007

Term of patent 7 years

(Cl. D7—5)

Figure 1 is a side elevational view of a sole embodying our design; the broken lines being utilized to indicate the sole as applied to a conventional boot;

Fig. 2 is an enlarged bottom plan view illustrating the tread surface of the sole portion;

Fig. 3 is a sectional view through the outer edge portion of the sole on a still further enlarged scale;

Fig. 4 is a detailed view showing a typical part of the horizontal trim on the outer rim of the sole, shown to the same scale as Fig. 3.

Fig. 5 is a section as seen on the line 5—5 of Fig. 2;

Fig. 6 is a section as seen on the line 6—6 of Fig. 2.

We claim:

The ornamental design for a sole, as shown and described.
